Bundy Tubing Company, Detroit, Mich., a corporation of Michigan

Application April 16, 1948, Serial No. 21,378

9 Claims. (Cl. 29—33)

1

This invention relates to an apparatus for shaping long work pieces into coils of serpentine form and it has to do particularly with the fashioning of tubing into serpentine coils.

An apparatus which embodies bending mechanism and other related parts for bending work pieces such as tube into the shape of serpentine coils, is fully disclosed and claimed in co-pending application Serial No. 687,668 filed August 1, 1946, and now patent No. 2,454,290. Such coils of tubing are useful as heat exchange devices and are admirably adapted for use in the refrigerating industry. A manufacturer of heat exchange equipment and particularly one which manufactures such equipment more or less on the production basis, sometimes requires that the dimensions of the coil and the locations of the ends of the tubing be accurately maintained. Where a length of tube is fed to a bending machine, the position of the leading end can be accurately maintained relative to the several bends of the coil. But as the tubing is fed to the machine, in a step by step manner, with successive bends made therein, it will be appreciated that certain variations unavoidably take place with the result that these variations are additive and all accumulate at the trailing end of the tube. One length of tube may be slightly harder or more tough than another and different locations along the length of a single tube may vary as to metal hardness or toughness resulting in some variation as to the position of the trailing end of the tube as the coil has been formed. The trailing end of the tube, accordingly, is liable to be misplaced considerably even though the work piece was accurately cut to a desired length before being bent into the serpentine coil.

The present invention aims to provide an improved apparatus which embodies a mechanism for bending tube into a serpentine coil and, with considerable automaticity, to stop the machine near the end of its operation in forming the coil and cut off the trailing end of the tube at an accurate location, treat the tube to remove burrs incident to the cutting operation and to then start the bending machine to make the final operations on the tube so that the trailing end of the tube is accurately located with respect to the remaining portion of the coil.

An apparatus for carrying out the invention is disclosed in the accompanying drawings.

Fig. 1 is a side elevational view of a machine for bending tubing into serpentine coils showing the cut off mechanism applied thereto.

Fig. 2 is an enlarged cross sectional view taken

substantially on line 2—2 of Fig. 1 showing parts of the cut off and burring mechanism.

Fig. 3 is a top plan view of the bending machine showing the bending rollers.

Fig. 4 is an enlarged view partly in section showing the bending head.

Fig. 5 is a view similar to Fig. 4 showing the bending head and its rollers in position at the completion of a bend.

Fig. 6 is a side elevational view illustrating the cutting and burr removing elements.

Fig. 7 is an end view of the cut off and burring mechanism with some parts cut away and some shown in section showing the parts in burr removing position.

Fig. 8 is a partial top plan view with some parts removed and some parts cut away, and others in section demonstrating the cutting operation.

Fig. 9 is a view showing a different position of the cooperating parts which are shown in the cut away part of Fig. 7.

Fig. 10 is a view showing the support for the cutter in side elevation.

Fig. 11 is a partial and elevational view looking at a control switch in a direction of the arrows 11—11 of Fig. 6.

Fig. 12 is a view showing the burring head and some of the mechanism controlled thereby and looking substantially on line 12—12 of Fig. 2.

The bending machine is shown as having a suitable base 1 from which extends, in an upward direction, a main bending oscillating shaft 2, while the table or support is shown at 3. A post 4 may extend upwardly from the table and may be provided with an overhanging arm 5 which may support mechanism for stabilizing the coil as it is swung in an oscillating fashion on the table 3. Such mechanism, however, may or may not be used depending upon the size of the coil and none is shown herein.

The shaft 2, as will be seen by reference to 4 and 5, has a cross head 7 mounted on which is a grooved bending roller 8 and a grooved bending roller 9. The tube, shown at 10, which may rest upon a suitable support or table 11 is fed between the rollers when the rollers are in the position shown in Fig. 4. The tube is fed axially by a pair of propelling rollers 12 mounted on a base 13 which can oscillate and reciprocate in supporting guides 13a. An oscillating bar 16 is connected to the base 13 and it has a head 14 with a pair of notches or recesses 15 which provide bearings for reduced portions 20 of the two bending rollers. The bar 13 has a clamp 17

applicable to the tube and is normally yieldably urged toward the bending rollers by a spring 18, the action of the spring being limited by a suitable stop 19.

In the operation of the bending machine the tube is fed into the machine, as shown in Fig. 4, the desired distance and then the feeding action is stopped and the clamp 17 applied. Starting from the Fig. 4 position, the shaft 2 oscillates to an extreme position, as shown in Fig. 5. Thus, the roller 9 forms or bends the tube as at B around the forming roller 8. Inasmuch as, in this action, the roller 8 is seated in its recess 15 and swung around the axis of the shaft 2, the bar 13 and the support for the feeding rolls are caused to oscillate which is permitted by the spring 18. From the position shown in Fig. 5, the shaft 2 oscillates back to the position shown in Fig. 4, and the tubing is again fed forwardly a determined amount. The clamp 17 is again applied to the tube and the shaft 2 now oscillates in the reverse direction to a position just opposite that shown in Fig. 5 to make the next succeeding bend in the length of the tube. In this action, the roller 9 seats in its recess 15 and the roller 8 fashions or forms the tube about the roll 9. Upon the making of this second bend, the shaft 2 oscillates back to the Fig. 4 position, the tube is fed forwardly again and one complete cycle of operation of the bending rollers is thus completed with two bends being formed. In this action, it will be appreciated that the coil, as shown in Fig. 3, is swung back and forth on the table 3. The leading end of the tube is the end shown at L with the series of bends at B made therein, while the trailing end of the tube is shown at T.

The cut off and burring mechanism are positioned just upstream from the propelling rollers 12 and may be disposed on a suitable base 25. There is a fixed central standard 26. This standard has an arm 27 for supporting a controlling electric switch operable by the tube. As shown in Fig. 11, the switch has a housing 28 and a bell crank member 29 pivotally mounted as indicated with an upper inclined end 30 which cooperates with an inclined surface 31 of a fixed recessed member, the bell crank being acted upon by a coil spring 33. A length of tube may be positioned by being pushed between the converging elements 30 and 31 and situated in a recess 32. When the end of the tube runs out of the recess the spring 33 actuates the bell crank to the dotted line position shown in Fig. 11, and this actuates the controlling switch 28 as will presently be seen. As will be noted by reference to Fig. 6, this switch and its operating arm is positioned upstream relative to the bending machine.

The central fixed member also carries a rather hook-shaped tube support 35 having a notch for receiving the tube as shown in Fig. 2. The support 35 is mounted on an arm 36 which is pivoted as at 37 and held normally against a stop 38 by a spring 39. The spring 39 reacts against a frame 40 and extending through the spring is a link 48 with a nut 49 adjusted against the side of the frame 40 opposite the spring. This support, as will be seen by reference to Fig. 6 and Fig. 3, is at the end opposite the switch 28 and adjacent the advancing rolls 12.

The frame 40 pivoted as at 41 and carries a cutting saw 42 pivoted as at 43 and driven by a belt 44. The belt runs over a pulley 45 which is driven by a motor 46 mounted on the pivoted support 40.

A second pivoted support 50, mounted as at 51, carries a driving motor 52 for operating a rotary

burr removing tool 53. Between the motor 52 and the burring tool 53 is a housing 54 which contains mechanism known to those versed in the art which causes the burring tool 53 to advance axially when the motor 52 is set into operation.

An air cylinder 56 with ports 57 and 58 into opposite ends is pivotally mounted on the frame 50 as at 59 and in the cylinder is a piston 60 which has a piston rod 61 pivotally connected to the fixed standard 26 as at 66.

There is a thrust connection between the pivoted supports 40 and 50, shown herein as in the form of a sleeve 62 pivotally connected to the frame 40 as at 63 with a rod 64 telescoping into the member 62 and pivotally mounted to the frame 50 as at 65. The member 62, as mentioned, is hollow but has a determined depth so that the end of the rod 64 may strike the bottom of the hollow portion. There are cooperating stops between the fixed frame 26 and the pivoted support 50 as shown respectively at 68 and 69. There is a controlling switch 70 having an actuating arm with a roller thereon, as shown at 71, arranged to be contacted and actuated by an actuator or stud 72 on the support 50.

The support 40 is yieldably acted upon by a coil spring 75 mounted on a rod 76 which is pivotally mounted to the support 40 as at 77. The rod extends through the fixed support 26 and through the support 50 with one end of the spring reacting against the support 26 and the other end acting upon the washer 78. This, as will be appreciated by reference to Fig. 2, places a load on the support 40 tending to swing it clockwise as Fig. 2 is viewed.

In the normal inactive position, the support 40 cannot swing under the action of the spring 75 because of a pivotally mounted blocker element 80 pivoted to the fixed standard as at 81 and having a roller 82 positioned to be abutted by a stop screw 83 on the frame 40. This blocker or detent 80 is acted upon by a spring 84 (Figs. 2 and 9) to hold it in normally blocked position as shown in Fig. 2. An actuating link 90 pivoted to the support 50 as at 91 (Fig. 9) is arranged to pass through an aperture 92 in the center standard 26 and the blocker 80 has an abutment or detent 93 to be acted upon by the link 90.

The burring tool, which may be covered by a protector 100, is arranged to effect certain controlling operations and, as shown in Fig. 12, it is provided with a collar 101 for acting upon a yoke of a lever 102 pivotally mounted at 103. This lever is acted upon by a coil spring 104 which keeps the yoke applied to the collar 101. Mounted on the fulcrum 103 to move with the lever 102 is an arm 109 having a finger detent 106 acted upon by a spring 107. The spring holds the detent against a shoulder 105. This arm is arranged to actuate the switch arm 108 of a controlling electric switch 110. With the arrangement shown, it will be appreciated that the finger 106 will actuate the switch arm 108 as the lever 102 swings in one direction but is ineffective thereon when the lever swings in the opposite direction. This mechanical operation of the switch 110 is but one way to accomplish the desired function as will presently be seen.

In the operation of the mechanism, and particularly during the time the bending mechanism is in operation making the bends in the work piece, as above pointed out, the tubing W lies in the recess 32 (Fig. 11) and thus the switch 28 is conditioned to maintain the operation of the bending machine. This switch is connected by suitable wiring to control mechanism (not shown)

for this purpose. The matter of electrical wiring is within the skill of anyone skilled in the art of electrical controls. The tubing may be fed forwardly with step by step movement with the bending head oscillating back and forth as above described in order to make the several bends in the tube.

The tubing also lies in the notch of the support 35 so that it is adequately supported adjacent the cutter blade 42. At this time, the mechanism is in the position shown in Fig. 2 with air under pressure maintained in the cylinder through the port 57. The spring 75 is under compression tending to pull the support 40 to the right but the support is blocked by the element 80. As soon as the trailing end of the tube moves out of the notch 32 the switch arm 30 swings under the action of the spring 31 and the controlling switch 28 is thereby actuated. This serves, through suitable control means (not shown) to stop the operation of the bending machine with the coil completely formed except for the last bend. More specifically, the trailing end of the tube will run out from under the arm 30 in the next to the last feeding action and then the bending machine will complete the next to the last bend and will come to rest in the position shown in Fig. 3. The actuation of the switch 28 also energizes the motor 46 for the operation of the saw and initiates entering air under pressure into the cylinder through port 58 with the port 57 connected to exhaust.

The machine has come to rest with the trailing end of the tube in approximately the position as indicated at T' in Fig. 3 with the tube adjacent its end supported because it lies in the notch of the support 35. The introduction of air into the cylinder through port 58 causes the pivoted support 50 start to move counter-clockwise on its pivotal mounting, due to the fact that the cylinder 56 is caused to move while the piston remains stationary because of its attachment to the center standard 26. This movement is a relatively steady constant movement as distinguished from a quick action and the link 90 engages the detent 93 and trips the blocker 80 to the position shown in Fig. 9. The frame 40 is thereby quickly released and the spring 75, which is under compression, quickly swings the frame 40 a few degrees clockwise on its pivotal mounting so that the saw 42, which is now rotating cuts through the tube. The tube is adequately supported on the bottom of the groove of the support 35 for this purpose. During the cutting action, it will be remembered that the frame 50 continues to swing counter-clockwise, as Fig. 2 is viewed. The frame 40 is so pulled by the spring until the frame strikes the stop 95 on the center standard 26. In this action, the support 36 remains in position although the spring 39 is compressed as the frame 40 shifts. This is because the support 36 is held against the stop 38. This movement of the frame 40, and the resultant sawing off of the end of the tube is very quickly accomplished. The relative position of the elements with severed end of the tube falling away is indicated in Fig. 8.

The frame 50 continues swinging counter-clockwise, as Fig. 2 is viewed, and the rod 64 ultimately seats in the bottom of the sleeve 62 and continued movement of the frame member 50 counter-clockwise pushes the frame 40 counter-clockwise on its mounting to a position as indicated in Fig. 7. In this action, the link 48 pulls the supporting arm 36 and the support 35 out of the way so that the burr removing tool may be positioned on the center of the work. In this

position the stop 68 strikes the stop 69 and the applied air pressure hold the parts in the position shown in Fig. 7 with the burring tool ready to operate.

As the support 50 approached a position where the burring tool is on the center of the tube the actuator 72 engages the arm 71 of the switch 10 to thus energize the motor 52 for the burr removing tool. The motor starts operating to rotate the burring tool 52 and it is advanced axially of the tube by the mechanism in housing 54 to the dotted line position shown in Fig. 12, thus burring the tube and then the tool retracts automatically. As the burr removing tool shifts to the right, as Fig. 12 is viewed, the finger 106 does not actuate the switch arm 108. As the burr removing tool moves back to the position shown in Fig. 12, the finger 106 momentarily actuates the swinging arm 108 which momentarily energizes switch 119. This has the effect of reversing the air in the cylinder 56. Air is now entered through the port 57 and the port 58 connected to the exhaust so that the swinging support 50 starts to swing clockwise from one position shown in Fig. 7 back to the at rest position shown in Fig. 2. One of the first things that happens is that the switch arm 71 is released so that the burr removing motor 52 is de-energized. It will be appreciated that the arm 90, after having tripped the blocking element 80, runs off of the detent abutment 93 and so the frame 40 follows the frame 50 back toward the position shown in Fig. 2 until the screw 83 strikes the roller 82 of the blocker element 80, the blocker element having been returned to blocking position by its spring 84. At this time the support 35 is again positioned to receive a tube.

The operator now places another tube in position by moving it downwardly between the relatively inclined parts 30 and 31 thus throwing the switch arm 30 and setting the machine into operation and discontinuing operation of the motor 46 which operates the saw. The new tube is positioned preferably so that its leading end abuts the sawed off and burred trailing end of the previous tube and as the switch 28 is thus energized, the bending machine is again conditioned for operation. The next bending operation will be that of swinging the coil (Fig. 3) clockwise to the dotted line position thus making the last bend of the coil. At the completion of the last bend the trailing end of the completed coil is in a position as indicated at T in Fig. 3. It was pushed into this position by the leading end of the next inserted length of tube which is shown at L' in Fig. 3. The completed coil is released from the clamp 17 and is removed from the machine as the new tube is advanced into position so that the first bend can be made thereon. This completes the cycle of operation and the bending machine continues to operate until the trailing end of the tube being operated on runs out from under the switch arm 30 which initiates the action of sawing off the trailing end and burring the same.

Thus, in reiteration, it will be observed that whenever the trailing end of a length of tube being operated on comes into position and releases the switch arm 30, that the bending operation ceases, the trailing end of the tube is cut off and then burred with the cut off saw and burring tool moving back to idle position, and the machine is set again into operation by the placement of the next length of tube to be worked.

I claim:

1. Apparatus for cutting and removing the burr from the end of a long work piece, such as tube, comprising, a first movably mounted support having a cutting tool normally positioned at one side of the work piece, a second movably mounted support having a burr removing tool positioned at one side of the work piece, means yieldably biasing the first support in a direction tending to cause the cutting tool to move into the work piece, a blocking element for preventing such movement of the said first support, operating means for moving the second support with the burr removing tool moving toward an axial position relative to the work piece, means operable by movement of the second support to release the blocking means for movement of the first support to cause the tool to cut off the trailing end of the work piece, means interassociated with the first and second supports so that continued movement of the second support moves the first support to position the cutting tool to one side of the work piece, means operable to actuate the burr removing tool to act upon the severed end of the work piece, and control means for causing the operating means to move the second support back to its initial position leaving the first support in its blocked position.

2. Apparatus for cutting and removing the burr from the end of a long work piece, such as tube, comprising, a first movably mounted support having a cutting tool normally positioned at one side of the work piece, a second movably mounted support having a burr removing tool positioned at one side of the work piece, means yieldably biasing the first support in a direction tending to cause the cutting tool to move into the work piece, a blocking element for preventing such movement of the said first support, operating means for moving the second support with the burr removing tool moving toward an axial position relative to the work piece, means operable by movement of the second support to release the blocking means for movement of the first support to cause the tool to cut off the trailing end of the work piece, means interassociated with the first and second supports so that continued movement of the second support moves the first support to position the cutting tool to one side of the work piece, means operable to actuate the burr removing tool to act upon the severed end of the work piece, and control means for causing the operating means to move the second support back to its initial position, said blocking means being restored to blocking condition as the second support moves to its initial position so as to block the first support in its initial position.

3. Apparatus for cutting and removing the burr from the trailing end of a long work piece, such as tube, which is being fed lengthwise comprising, a fixed standard positioned substantially on the center line of the work piece, a first pivoted support on one side of the standard having a cutting tool thereon, a spring acting upon the support and reacting against the standard tending to move the support in a direction so that the cutting tool moves toward the work piece, a movable blocking element on the standard for blocking the first support and preventing such movement, a second support pivotally mounted on the other side of the standard, a burr removing tool carried by the second support, operating means for swinging the second support to shift the burr removing tool toward the work piece, a movable

controlling element carried by the standard and actuated as the trailing end of the tube moves therefrom to set the last mentioned means into operation, a trip member on the second support for tripping the said blocking means for movement of the cutting element into the work piece to sever the trailing end thereof as the second element is moving toward the work piece, interengaging means on the two supports for causing the second support to shift the first support thereby moving the cutting tool away from the work piece so that the burr removing tool may be positioned on the axis of the work piece, control means operated by the second support to set the burr removing tool into operation substantially when the said tool is on the axial center of the work piece, control means actuated by the movement of the burr removing tool to cause the operating means to move the second support back to its original position, and a spring operative upon the blocking means to position the same to block the first support in its initial position as the second support moves back to its initial position.

4. Apparatus for cutting and removing the burr from the trailing end of a long work piece, such as tube, which is being fed lengthwise comprising, a fixed standard positioned substantially on the center line of the work piece, a first pivoted support on one side of the standard having a cutting tool thereon, a spring acting upon the support and reacting against the standard tending to move the support in a direction so that the cutting tool moves toward the work piece, a movable blocking element on the standard for blocking the first support and preventing such movement, a second support pivotally mounted on the other side of the standard, a burr removing tool carried by the second support, operating means for swinging the second support to shift the burr removing tool toward the work piece, a movable controlling element carried by the standard and actuated as the trailing end of the tube moves therefrom to set the last mentioned means into operation, a trip member on the second support for tripping the said blocking means for movement of the cutting element into the work piece to sever the trailing end thereof as the second element is moving toward the work piece, interengaging means on the two supports for causing the second support to shift the first support thereby moving the cutting tool away from the work piece so that the burr removing tool may be positioned on the axis of the work piece, control means operated by the second support to set the burr removing tool into operation substantially when the said tool is on the axial center of the work piece, control means actuated by the movement of the burr removing tool to cause the operating means to move the second support back to its original position, a spring operative upon the blocking means to position the same to block the first support in its initial position as the second support moves back to its initial position, a supporting element for the work piece pivotally mounted to the standard and positioned adjacent the cutting tool, a spring for holding the supporting element in position to support the work piece as the cutting tool acts thereon, and means interconnecting the supporting element and the first named support for shifting the supporting element away from the work piece as the second support shifts the first support.

5. An apparatus for performing operations on long work pieces, such as tube, comprising,

for feeding a work piece lengthwise with step by step action, mechanism for performing operations on the work piece between each feeding step, control means actuated by the presence of a work piece for continued operation of the feeding means and mechanism, said control means being actuated as the trailing end of the work piece passes the same to thereby discontinue operation of the said feeding means and said mechanism, a cutting tool, a movable support for the tool, and means set into operation by said control means, upon said actuation thereof, for moving the support while the work piece is at rest for causing the tool to cut off the trailing end of the work piece.

6. An apparatus for performing operations on long work pieces, such as tube, comprising, means for feeding a work piece lengthwise with step by step action, mechanism for performing operations on the work piece between each feeding step, control means actuated by the presence of a work piece for continued operation of the feeding means and mechanism, said control means being actuated as the trailing end of the work piece passes the same to thereby discontinue operation of the said feeding means and said mechanism, a cutting tool, a support for the tool mounted for back and forth movement, the tool being normally spaced from the work piece, and means set into operation by said control means, upon said actuation thereof, and operable while the work piece is at rest, for moving the support to cause the cutting tool to cut across the work and thereby sever its trailing end, and then to move back to a position with the cutting tool spaced from the work piece.

7. An apparatus for performing operations on long work pieces, such as tube, comprising, means for feeding a work piece lengthwise with step by step action, mechanism for performing operations on the work piece between each feeding step, control means actuated by the presence of a work piece for continued operation of the feeding means and mechanism, said control means being actuated as the trailing end of the work piece passes the same to thereby discontinue operation of the said feeding means and said mechanism, a cutting tool, a movable support therefor, a burr removing tool, a movable support therefor, and means set into operation by said control means, upon said actuation thereof, and operable to move said supports in timed relationship to cause the cutting tool to sever the work piece and to move back from the work piece and to move the burr removing tool onto the axis of the work piece for acting upon the trailing end thereof and then for moving the burr removing tool off the axis of the work piece.

8. An apparatus for performing operations on long work pieces, such as tube, comprising, means for feeding a work piece lengthwise with step by step action, mechanism for performing operations on the work piece between each feeding

step, control means actuated by the presence of a work piece for continued operation of the feeding means and mechanism, said control means having an element which is actuated as the trailing end of the work piece passes the same to thereby discontinue operation of the said feeding means and said mechanism, a movably mounted cutting tool, a movably mounted burr removing tool, means set into operation by said control means, upon said actuation thereof, for moving the cutting tool to cause the same to sever the trailing end of the work piece and then to move away from the work piece, and for moving the burr removing tool onto the axis of the work piece for acting upon the severed trailing end to remove the burrs therefrom, and for shifting the burr removing tool off the axis of the work piece, said element of said control means being actuated upon the placing of another work piece in position, for resumption of operation of the said feeding means and said mechanism.

9. An apparatus for performing operations on long work pieces, such as tube, comprising, means for feeding a work piece lengthwise with step by step action, mechanism for performing operations on the work piece between each feeding step, control means actuated by the presence of a work piece for continued operation of the feeding means and mechanism, said control means having an element which is actuated as the trailing end of the work piece passes the same to thereby discontinue operation of the said feeding means and said mechanism, a cutting tool, a pivotally mounted support therefor, a burr removing tool, a pivotally mounted support for the burr removing tool, means set into operation by said control means, upon said actuation thereof, and operable while the work piece is at rest, for oscillating the support for the cutting tool to cause the same to sever the trailing end of the work piece and for oscillating the support for the burr removing tool, to place the burr removing tool on the axis of the work piece for acting upon the same to remove burrs therefrom, and for shifting the burr removing tool away from the axis of the work piece, said element of the said control means being actuated upon the insertion of another work piece for the resumption of the operation of the feeding means and mechanism.
